MULTIPLYING MACHINE

William Lang, New York, N. Y., assignor to
 International Business Machines Corporation,
 New York, N. Y., a corporation of New York

Application May 27, 1936, Serial No. 82,082

12 Claims. (Cl. 235—61.6)

This is a continuation in part of application Serial No. 55,509, filed December 21, 1935.

This invention relates to improvements in accounting machines and more particularly to multiplying accounting machines.

The present invention has for one of its objects the provision of an improved type of multiplying machine in which the method of computation, technically known as duplication, is employed. By this method, a multiplicand is repeatedly doubled to build up the product.

A further object of the present invention resides in the provision of a multiplying accounting machine adapted to effect multiplication by first 15 effecting a separate setting of the multiplicand for each denominational order of the multiplier and thereafter automatically raising each entry to the product of the multiplicand times the associated multiplier digit, so there will be a setting 20 of a number of sub-products, each representing the multiplicand times a digit of the multiplier. These sub-products are thereafter gathered or added together to produce the final product.

A further object of the invention is to provide 25 mechanism wherein the number of operations required to obtain the several sub-products varies according to the value of the multiplier.

A further object of the present invention resides in the provision of a machine in which the 30 construction is simplified and improved for ease of assembly and maintenance.

A further object of the invention is to provide 35 a machine in which a plurality of accumulators are provided and in which the entries may be repeatedly doubled and in which the number of repetitions for each accumulator is variable.

Various other objects and advantages of the invention will be obvious from the following particular description of two forms of mechanism 40 embodying the invention or from an inspection of the accompanying drawings; and the invention also constitutes certain new and useful features of construction and combination of parts herein- 45 after set forth and claimed.

In the drawings:

Figs. 1, 1a, and 1b, taken together and arranged vertically in the order named, show the wiring diagram of the electric circuits of the machine.

Fig. 2 is a view showing the manner in which 50 a typical computation is performed by the machine.

Fig. 3 is a view showing a further example and the manner of its computation as performed by the machine.

Fig. 4 is a view showing the driving mechanism for feeding the record cards.

Fig. 5 is a view showing the card advancing and analyzing mechanism.

Fig. 6 is a view showing the accumulator re-setting mechanism.

Fig. 7 is an isometric view showing one order of the accumulator mechanism.

Fig. 8 is a timing chart showing the timing of the electrical devices of the machine.

10

Fig. 9 is a sectional view of the printing mechanism.

Fig. 10 is a view of a controlling record card in which multiplicand and multiplier factors are perforated.

Fig. 11 is a portion of the circuit showing a modified arrangement.

Fig. 12 is a further portion of the circuit showing a modified arrangement.

Before describing the construction of the machine to which the present invention is shown applied, the general principles under which the machine operates and the general mode of operation will be set forth.

According to the present invention the machine 25 carries out multiplication in the following manner. The record card bearing the two factors to be multiplied is first advanced to pass two analyzing stations. At the first station the multiplier factor is read to determine the number of computing cycles required for the problem. At the second station the multiplicand is analyzed and this factor is entered into as many separate accumulators as there are possible positions in the multiplier. In addition, a further entry is made 30 into a so-called MC accumulator. This entry is represented diagrammatically in Fig. 2 where 642 represents the multiplicand and 375 represents the multiplier. Under the column headed "Cycles," it is indicated that during the first cycle 40 the multiplier is read. On the line indicated "Enter MC" it is seen that the value 642 is entered into the four accumulators. In the following computing cycles, it is the object to increase the initial entry of 642 in ACC#1 to 1926, which 45 represents three times the multiplicand. In ACC#2 it is desired to increase the multiplicand to 4494, which is seven times the multiplicand; and in ACC#3, it is the object to increase the entry to 3210, which is five times the multipli- 50 cands.

This raising of the initial entry in each accumulator to the desired sub-product is brought about by what will hereinafter be termed "doubling" operations and "transfer" operations.

- A "doubling" operation is represented in Fig. 2 by the curved arrows pointed downwardly to the next line, indicating that the amount in the accumulator is added to itself or doubled. A "transfer" operation is indicated by an arrow extending from the amount in the MC accumulator to one of the other three accumulators, indicating that the amount standing in the accumulator MC has been added to such other accumulator.
- 10 In ACC#1 the sub-product of three times the multiplicand is obtained by doubling the initial entry once and transferring from the MC accumulator once. In ACC#2 the sub-product of seven times the multiplicand is obtained by doubling the entry twice and transferring the amount in the MC accumulator three times in succession; and the sub-product in ACC#3 is obtained by doubling twice and transferring once.
- The following table summarizes the manner 20 in which the sub-product of a multiplicand times any of the digits is obtained in the machine:

TABLE I

MP digit	3rd cycle	4th cycle	5th cycle	6th cycle	7th cycle
9	Double	Double	Double	Transfer	
8	do	do	do		
7	do	do	Transfer	do	
6	do	do	do	do	
5	do	do	do	do	
4	do	do	do		
3	do	do	Transfer		
2	do	do			
1					
0	(Disable entering)				

- 35 According to Table I the maximum number of cycles required to obtain the several sub-products is five and if the multiplier digit contains a "7" digit, five cycles will be taken by the machine to obtain the several sub-products. If 40 the multiplier factor contains a digit "5" but no "6", "7", or "9", then the sub-products will be obtained in three cycles, and if the highest digit in the multiplier factor were "2", a single cycle would suffice to obtain the sub-products.
- 45 In Fig. 3 is shown a problem in which the multiplier factor is 104 and it will be observed that ACC#1 is to compute a sub-product of the multiplicand times one; ACC#2 the multiplicand times zero; and ACC#3 the multiplicand times four.

50 In Table I it will be observed that four times the multiplicand is obtained by doubling twice so that only two computing cycles are required to obtain such sub-products and after the doubling and transferring operations are completed, the multiplicand times one will stand in ACC#1, and MC times four will stand in ACC#3. Where zeros occur in the multiplier, the initial entry of the multiplicand into the associated accumulator is suppressed so the entry therein remains zero.

55 Referring back to Fig. 2, after the doubling and transferring operations, the amounts 1926, 4494, and 3210, representing three times, seven times, and five times the multiplicand, will stand in the accumulators. The next operation is to add these amounts together with proper provision for the correct denominational allocation. This operation of adding these amounts together 60 will hereinafter be termed "gathering" to distinguish over the aforementioned transfer operations.

70 Thus, the amount in ACC#1 is entered into ACC#3 during the eighth cycle and during the ninth cycle the amount in ACC#2 is entered

into ACC#3, giving a total or final product of 240,750, which, during the subsequent cycle, is printed on a suitable record and all of the accumulators are then reset to zero.

The accounting machine to which the present invention is shown as applied, so far as the mechanical construction is concerned, is similar to the machine shown and described in Patent No. 1,976,617, granted October 9, 1934, to C. D. Lake and G. F. Daly, to which reference may be had for a fuller description of the general operation of the various units and the manner of drive. There are certain differences in the present construction over the machine shown in the above mentioned patent which will be pointed out hereinafter.

In the following, the separate units of the machine will first be described to explain their manner of operation, after which the circuit diagram will be described to point out the manner in which the several units are coordinated.

Card feeding mechanism

The card feeding mechanism shown in Figs. 4 and 5 is exactly similar to that shown and described in the patent referred to, except that provision is made in the form of a clutching device for interrupting the card picker operations without stopping the accumulating drive mechanism. In Fig. 4, 10 represents the drive shaft of the machine which may be directly connected or detachably coupled to a suitable driving motor.

In Fig. 5, the analyzing brushes are indicated at UB and LB and the record cards R are successively advanced by picker 11 to a first pair of feed rollers 12 which serve to advance the cards to further pairs of feed rollers 13 which advance the cards to pass the upper and lower brushes in succession. The shafts upon which rollers 13 are mounted are provided with gears 14 at their extremities and arranged as shown in Fig. 4 to be driven through gearing 15 from gear 16 on the drive shaft 10. It is thus seen that the rollers 13 are in constant rotation. From one of the gears 15 a gear 17 is driven through an idler 18, 45 which gear 17 is freely mounted upon a shaft 19. Secured on shaft 19 is a gear 20 which serves to drive the picker mechanism and the first pair of feed rollers 12. Also secured on shaft 19 is a clutch arm 21 carrying a spring-pressed dog 22, 50 which dog and arm are normally latched in the position shown by latching armature 23 pivoted at 24 and controlled by a magnet 25.

Energization of magnet 25 will release dog 22 for engagement with driving element 26 which is secured to the constantly running gear 17 so that gear 20 will be driven for one revolution during which the picker 11 will advance the record card from the magazine to rollers 12 which feed it to the dotted line position indicated in Fig. 5, where the leading edge of the card is beneath the brushes UB.

At each brush station, there is provided a pair of card lever contacts designated UCL and LCL, which are operated by the usual card levers to close as the record card passes the station and to remain open unless a card is present. During the doubling, transferring, gathering, and product printing cycles, magnet 25 is deenergized and card feeding will, of course, not take place 70 during such cycles.

Accumulating mechanism

The adding mechanism is entirely similar to that shown and described in the patent referred

to and the description thereof will accordingly be limited to a brief explanation of its manner of operation. The drive shaft 27 (Fig. 7) is directly geared to the main shaft 10 in Fig. 4 so that it is in operation as long as the driving motor of the machine functions and the driving ratio is such that shaft 27 makes one revolution for each card feeding cycle of the machine. The shaft 27 has slidably mounted thereon but keyed for rotation therewith a clutch element 28, one for each denominational order of the accumulator. The element 28 is provided with a groove in which fits the end of a short arm of a lever 29 which is pivoted as shown and provided with a block 30 normally held as in Fig. 7 by armature latch 31 of adding magnet 32.

A leaf spring 33 bears against the extremity of the longer arm of lever 29 and moves the same in a counterclockwise direction upon release of block 30 by armature 31. This movement will bring clutching member 38 into engagement with cooperating teeth 34 integral with a gear 35 loosely mounted on shaft 27. Gear 35, when thus coupled to shaft 27, will rotate a gear 36 which meshes therewith and will displace the accumulator index wheel 37. The rearward extremity of member 29 is adapted to be engaged by a finger 38 toward the end of the cycle for the purpose of disengaging clutching element 28 from teeth 34 and relatching block 30 on armature 31.

Briefly summarizing the adding operation, the magnet 32 may be energized at various points in the cycle of the machine depending upon the location of a perforation in a column of the card analyzed by the lower brushes LB. This energization may take place in response to a perforation in any of the index point positions from 9 to 1, inclusive. A perforation in the 9 index point position will trip the clutch element 28 nine steps before finger 38 is operated to declutch it and a perforation in the 1 index point position will trip the clutch element 28 before it is declutched by the finger 38. Each step of clutching engagement corresponds to a tenth of a revolution of the accumulator index wheel 37 so that a 9 hole will cause it to move nine-tenths of a revolution and the 1 hole will cause it to move one-tenth of a revolution. The manner in which circuits through the lower brushes LB control the operation of magnet 32 will be set forth in connection with the explanation of the circuit diagram. Suitable carry mechanism between the several orders of the accumulator mechanism are provided, and these are exactly similar to that shown in the Patent No. 1,976,617 so that illustration thereof is omitted.

Readout mechanism

Also driven by gear 35 (Fig. 7) is a gear 39. Since the ratio of gears 39 and 35 is 2:1, the former will turn through a half revolution for each revolution of the latter. Carried by and insulated from gear 39 is a pair of electrically connected brushes 40, one of which cooperates successively with ten conducting segments 41, while the other cooperates with an arcuate conducting strip 42.

The relationship of the parts is such that when the index wheel 37 is in its zero position, one of the brushes 40 is in contact with the zero segment 41 and the other brush is in contact with the strip 42, thus forming an electrical connection between the two. If the wheel 37 is displaced to indicate, say, 8, then one of the brushes 40 will be in contact with the 8 segment 41 and

the other brush will be in contact with the arcuate strip 42. The positioning of the brushes 40 provides a convenient electrical readout mechanism for controlling doubling, transferring, gathering, and product printing operations, and the electrical circuits involved in these functions will be more fully explained in connection with the circuit diagram.

Printing mechanism

The printing mechanism is shown in Fig. 9 where the usual so-called listing shaft 43 carries a clutch driving element 44. The shaft 43 has direct driving connection with the constantly running shaft 10 (Fig. 4) so that clutch driving element 44 may rotate continuously. The listing cam 45 is freely carried on the shaft 43 and provided with a spring-pressed clutching dog 46 adapted for engagement with the driving element 44. Dog 46 is normally held out of engagement by arm 47 controlled by magnet 48.

Energization of magnet 48 will permit cam 45 to rotate with the listing shaft 43 and follower arm 49 will cause oscillation of rocker shaft 50 to which are secured arms 51 link-connected to the reciprocating crosshead 52 so that for each revolution of cam 45, crosshead 52 will be moved upwardly and then down again to its initial position. Slidably mounted in the crosshead are type bars 53 spring urged into movement with the crosshead as it rises. As type bar 53 moves upwardly, ratchet teeth 54 successively pass the nose of stopping pawl 55 as the type elements 56 successively pass printing position opposite platen 57.

Energization of printing magnet 58 as the type bar moves upwardly will draw call wire 59 toward the right to rock the latch 60 out of engagement with stopping pawl 55 whereby the nose of the latter will engage one of the teeth 54 and interrupt further upward movement of the type bar. Before the crosshead 52 moves downwardly, the usual printing hammers are tripped to take an impression from the selected type elements.

Accumulator resetting mechanism

The shaft 61 (Fig. 6) upon which the index wheels 37 of an accumulator are loosely mounted is slotted for cooperation with spring-pressed pawls (not shown) pivoted upon and carried by the individual index wheels in such manner that counterclockwise rotation of shaft 61 will engage and drive the index wheels 37 forwardly to zero position during a single revolution of shaft 61.

Referring to Fig. 6, shaft 61 carries a gear 62 at its extremity which is in engagement with gear 63 mounted upon reset shaft 64. Gear 63 of which there is one for each accumulator may be selectively coupled to the resetting shaft 64 in the well known manner more fully explained in the patent above referred to. At the extremity of shaft 64 is a gear 65 which is adapted to be driven by an intermittent gear 66 which is secured to shaft 61. Also fixed to shaft 67 is an arm 68 which carries spring-pressed clutch dog 69 normally held in the position shown in Fig. 6 by a latching arm 70 supported by armature shaft 71 of magnet armature 72. Energization of magnet 73 will release dog 69 for engagement with clutch driving element 74. Element 74 is integral with a gear 75 which meshes with a gear 76 secured upon constantly running shaft 43.

With this arrangement, driving element 74 is in constant rotation and whenever it is desired to effect resetting of the accumulators, magnet 73 is energized to provide a connection between 5 the element 74 and the resetting shaft 64.

General explanation of the circuit diagram

The wiring diagram of the electric circuits of the machine is shown in Figs. 1, 1a and 1b, 10 wherein the various cam controlled contact devices are diagrammatically shown and suitably labelled L, CR, or TP for identification. The cams prefixed L operate only during the card feed cycle. The cams prefixed TP operate only 15 during the total print and reset cycle, while those prefixed CR and the emitters prefixed E are in constant operation. The timing of these contact devices is shown in the timing diagram (Fig. 8) to which reference may be made for 20 the actual time in the cycle of operations during which they function.

In this figure the dark lines represent the period during which the cam contacts are closed. Due to the numerous circuit connections involved 25 in the present arrangement, it has not been advisable in all instances to show the relay magnets and their associated contacts in close proximity to one another. For purposes of clarity in the wiring arrangement, the relay contact points 30 are shown in the circuits which they control and their relay magnets are dotted adjacent thereto. Further, the different contacts are designated with the same reference character as the controlling magnet, followed by a numeral. The 35 complete circuit diagram will now be described in detail and the various operations will be set forth in the order of their occurrence.

For each record card there will be a number of cycles determined by the value of the multiplier 40 digits. Of these cycles for each card there will be first, two cycles during which the card is moved to pass the upper and lower brushes in succession. Following this will be a variable number of doubling and transfer cycles, after 45 which will follow two so-called gathering cycles, and then the product printing and resetting cycle, thus making five invariable cycles, plus from one to five variable cycles for each computation. During each of the two card feeding 50 cycles, the cam contacts operate in accordance with the timing shown in the left hand third of the diagram of Fig. 8. During each of the doubling and transfer cycles and also during each of the gathering cycles, the operation is in accordance with the central third of Fig. 8. During 55 the product printing and resetting cycle the operation is in accordance with the right hand third of the diagram. For a card having a problem requiring but one variable cycle, therefore, there will be two card feed cycles (with cam timing as in the first third of Fig. 8), three cycles of doubling and gathering (as in the second third of Fig. 8) and a final cycle of printing (as in the last third of Fig. 8).

60 *Starting cycles.*—Referring to Fig. 1, the switch 71 is first closed to connect the motor M between the main lines 80 and 90. With the motor M in operation, the several constantly rotating shafts and the CR cams and emitter brushes commence 70 rotation. At the very commencement of operations, the brush of emitter E4 (Fig. 1) is permitted to make a number of turns before the start key is operated. This is for the purpose of effecting a preliminary set-up of the relays generally designated C near the bottom of Fig. 1;

that is, during the first turn when the brush is on the g segment, a circuit is traceable from line 80 through wire 89, brush of emitter E4, segment g, wire 91, relay magnet C, and then serially through the contacts 1B1, 2B1, 3B1, 4B1, 5B1, 6B1, wire 84 to line 90. Relay C closes its contacts C1 to provide a holding circuit through wire 85 and also closes its contacts C2 and C3. During the next cycle, when the brush of emitter E4 is on the f segment, a circuit is traceable through 10 contacts C3, relay magnet 1C and thence serially through the contacts 1B1 to 6B1 to line 90. On the third cycle, when the brush of the emitter is on the segment e, the circuit is traceable through contacts 1C3, relay magnet 2C, then in series 15 through contacts 2B1—6B1 to line 90. In this manner the relay magnets C to 6C are energized in turn and a holding circuit is provided to maintain them energized. This is the condition in which they are shown in Fig. 1 in readiness for the depression of the start key. Depression of the start key to close contacts 78 will cause energization of the card feed clutch magnet 25 and the card picker mechanism will operate to feed the first card from the magazine to the first pair of rollers 12.

At the end of this cycle, the card will be at the dotted line position shown in Fig. 5. A second depression of the start key 78 will again energize magnet 25 and the first card R will advance to 30 pass the upper brushes UB while the second card is advanced by the picker 11.

As the brushes UB traverse the multiplier field of the card, circuits will be completed through the perforations representing the multiplier 35 factor. It may be here explained that in the circuit diagram, sufficient mechanism has been shown to handle a three place multiplier and a three place multiplicand. This has been done to obviate the repetition of similar parts.

As the index point positions 9, 8, 7, etc., are successively sensed by the brushes, the brush of emitter E1 contacts the segments thereof in the order 9, 8, 7, etc. During the sensing of the positions 9 to 1, inclusive, cam contacts L1 are 45 closed and during the sensing of the zero positions, contacts L2 are closed and contacts L1 are open. Assuming, for example, a perforation in the "1" index point position, a circuit will be completed from line 80 to cam contacts CR8, 50 card lever contacts UCL1, brush UB, plug connection 79, cam contacts L1, wire 81, brush of emitter E1, the "1" segment of emitter E1, wire 82, relay magnet 1B, wire 83, to line 90. It will be observed that with the contacts L1 closed, a 55 circuit through any of the brushes UB in the multiplier field will complete a circuit through the wire 81 and that as many relay magnets 1B, 2B, etc. may be energized as there are different significant figures in the multiplier factor. The 60 function of these relay magnets is to control the number of variable cycles which the machine is to perform and the controlling is in accordance with Table I above.

During the analysis of the zero positions, 65 circuits will be completed through those positions in which zeros occur, which are traceable from line 80, contacts CR8, UCL1, brush UB, plug connection 79, contacts L2 (contacts L1 are open at this time), relay magnets 1A, 2A or 3A, wire 83 to 70 line 90. Relay magnet 1A will close its contacts 1A1 to provide a holding circuit extending from line 80, cam contacts L3, contacts 1A1, magnet 1A, wire 83, to line 90. The function of the magnets 1A, 2A and 3A is to suppress the entry into 75

accumulators in those orders which are associated with columns in which zero is present in the multiplier factor.

Cycle controlling circuits.—At the bottom of Fig. 1 is shown a group of relays designated C, 1C, 2C, etc., which determine the number of variable cycles which are to be performed. These relays are normally energized through circuits of which the following for magnet C is representative: This circuit follows from line 90, wire 84, serially through contacts 6B1, 5B1, to 1B1, magnet C, contacts C1, wire 85, to line 80. This initially setup circuit is prepared, when cards are fed through the machine in succession, during the last computation and the manner in which it is set up when the machine is first started has already been explained.

Energization of any magnet 1B to 6B will shift its contacts from the position shown and will interrupt the just traced holding circuit at such point to deenergize the related magnets C to 6C and all magnets of lower order. For example, if magnet 6B were energized in response to the analysis of a "7" perforation, contacts 6B1 would open momentarily and all the magnets C to 6C would be deenergized. If magnet 3B were the highest order magnet in its group to be energized, it would open its contacts 3B1 and cause deenergization of magnets C, 1C, 2C and 3C while magnets 4C, 5C, and 6C remain energized.

Energization of any of the B magnets will close a pair of contacts 1B2 to 6B2, as the case may be, to establish a circuit from line 90, wire 84, contacts 6B2, for example, wire 86, a relay magnet Y, wire 87, resistance 88, to line 80. Relay magnet Y closes its contacts Y1 which provide a holding circuit from line 90, contacts Y1, magnet Y, wire 87, resistance 88, to line 80 and this holding circuit is maintained until the C magnets which have been deenergized are again set up in the manner which will now be explained. It may here be explained that the magnet Y, upon energization, opens a pair of contacts Y2 in the upper part of Fig. 1, before cam contacts CR3 in series therewith are closed. Thus, during the cycle in which the record card passes the upper brushes, the B magnets are selectively energized and the contacts of any one thereof will cause energization of magnet Y which in turn, by opening its contacts Y2, will prevent energization of magnet 1G during this cycle. The function of magnet 1G will be explained hereinafter.

During the second card feed cycle which is the cycle following that in which the card passes the upper brushes and the multiplier factor is sensed to condition the relay magnets C to 6C, the brush of emitter E4 successively traverses its contact segments a, b, c, d, e, f, and g, and a circuit is first completed through the g segment which is traceable from line 80, wire 89 (Fig. 1), emitter brush and segment g, wire 91, relay magnet C, contacts 1B1 to 6B1 (which contacts are now closed), wire 84, to line 90. Energization of magnet C will close its contacts C1, C2, and C3. Contacts C1 set up the holding circuit for magnet C and contacts C3 connect the next magnet 1C in circuit with the commutator segment f. During the next following cycle, the emitter brush will complete a circuit through the segment f and contacts C3 to energize relay magnet 1C, which in turn will close its contacts 1C1, 1C2, and 1C3, providing a holding circuit and also connecting the next higher magnet 2C to the commutator segment e.

If it be assumed that one of the multiplier

digits sensed by the upper brushes is "7" and that such analysis caused momentary energization of relay magnet 6B, all of the magnets C to 6C would have been deenergized and the emitter E4 would thereafter successively reenergize the C magnets, one in each of the series of successive cycles. The C magnet is energized during the latter part of the same cycle in which the card passes the upper brushes and the multiplier is sensed. The 1C magnet is energized in the next cycle during which the card passes the lower brushes and the multiplicand factor is sensed. The remaining magnets 2C to 6C are energized in the following cycles and in order.

When all the C magnets are energized, a circuit is traceable from line 80, resistance 88, contacts C2, 1C2, 2C2, etc., to 6C2, contacts Y1, to line 90. This circuit through resistance 88 short circuits the relay Y, causing it to become deenergized. Deenergization of magnet Y will cause the machine to automatically enter upon the so-called gathering cycles of operation.

If sensing of the multiplier factor resulted in deenergization of only the first three magnets C, 1C and 2C, then this short circuit will be completed after three cycles of operation, that is, after these magnets have been reenergized in succession.

In Fig. 1 are shown contacts Y2, which, upon deenergization of magnet Y will close to complete a circuit from line 80, upper card lever contacts UCL2, relay magnet 1G, contacts Y2, cam contacts CR3, contacts P3, contacts 2G1 to line 90. Magnet 1G will close its contacts 1G5 to provide a holding circuit from line 90, cam contacts CR4, contacts 1G5, magnet 1G, card lever contacts UCL2, which are closed due to the presence of a card at the upper brush station, to line 80. Magnet 1G controls gathering operations which will be explained in detail later. During such operations, cam contacts CR5 close. These contacts are timed to close momentarily and open again before cam contacts CR3 close. A circuit is thereby established which is traceable from line 90, contacts CR5, relay contacts P2, contacts 1G6, relay magnet 2G, to line 80. Magnet 2G closes its contacts 2G5 to provide a holding circuit through cam contacts CR6 and at the same time opening of contacts 2G1 prevents reenergization of the magnet 1G.

Magnet 2G controls gathering operations during the second gathering cycle and during this cycle cam contacts CR7 close momentarily to establish a circuit from line 90, contacts CR7, relay contacts 2G6, relay magnet P, to line 80. Magnet P will close its contact P1 to provide a holding circuit through cam contacts TP4 and the consequent opening of contacts P2 and P3 will prevent further energization of the magnets 1G or 2G.

The magnet P controls the total printing circuits as will be explained and in addition closes a pair of contacts P4 at the top of Fig. 1 which will complete the circuit through the print cam clutch magnet 48 and the reset clutch magnet 73 to initiate a cycle of operation of these mechanisms. During the total printing cycle, during which the TP cams operate, contacts TP3 close to energize the card feed clutch magnet 25 after the accumulators have been cleared and the next following card will proceed to pass the upper brushes.

Entering circuits.—The manner in which the amounts are entered into the accumulators will now be explained and the control circuits traced.

It has been pointed out that as the card traverses the upper brushes during the first card feed cycle, magnets 1B to 6B are energized to determine the number of cycles required for the card sensed.

- 5 It may be mentioned at this point that for each card passing through the machine, there are two card feed cycles, the first card feed cycle being that in which the card traverses the upper brushes and the second being the cycle in which 10 it traverses the lower brushes. As is common in other multiplying and statistical machines generally, when the machine is first started, there is an additional feeding cycle required to bring the very first card into position in readiness to 15 pass the analyzing brushes so that at the very commencement of operations there are in fact three card feeding cycles but that for the succeeding cards only two take place, because as the first card passes the upper brushes, the next 20 succeeding card is advanced from the hopper to a position in readiness to pass the upper brushes when computations have been completed under control of the first card. To avoid confusion, therefore, "first card feed cycle" designates the 25 cycle in which the card passes the upper brushes and "second card feed cycle" designates the cycle in which the card passes the lower brushes. As the card continues downwardly to pass the lower brushes LB during the second card feed cycle, the 30 multiplicand amount is entered into the four accumulators MC, #1, #2, and #3. The entering circuits are traceable (Fig. 1b) from line 90, through cam contacts CR9, card lever contacts LCL, lower brush LB, and through plug connection 35 91 to socket 92 and adding magnet 32 of accumulator MC. From socket 92 of accumulator MC, connections 93 are made as shown to sockets 94 which have connections with relay contacts 1A2, 2A2, and 3A2, as indicated.
- 40 Between these contacts and the sockets 92 of these three accumulators are contacts H2 plug connected as shown. The contacts H2 are provided to prevent undesirable back circuits and are controlled by relay magnet H, shown in Fig. 1.
- 45 The operation is as follows:

As the card moves to pass the upper brushes, the relay magnet H is deenergized and contacts H2 are open. Toward the end of this first cycle, the cam contacts L4 close to energize the relay H thereby closing its contacts H1 to establish a holding circuit through cam contacts CR1. The contacts CR1 maintain magnet H energized through that portion of the next following cycle during which the card traverses the lower brushes 55 so that at such time the contacts H2 are closed and they are open at all other times.

As explained above, the relay magnets 1A, 2A, and 3A (Fig. 1) are energized in response to the presence of zeros in the multiplier factor. Thus, 60 if the units order of the multiplier were zero, magnet 3a would have been energized and its contacts 3A2 consequently opened so that ACC#3 would receive no entry from the brushes LB.

Doubling circuits.—When an amount is to be read out of one of the accumulators and re-entered therein to effect doubling of the amount, a plug connection 95 (Fig. 1b) is made between the plug socket 96 of that accumulator and relay contacts 1D2, and a further plug connection 97 is made from the contacts 1D2 to socket 92 of the same accumulator.

Upon closure of contacts 1D2, a circuit is traceable as follows: from line 90, wire 98, emitter E2, through wires 99, readout segments 41, brushes 40, common strip 42, socket 96, connection 95,

contacts 1D2, connection 97, socket 92, adding magnet 32, to line 80. The adding magnet 32 of the accumulator will thus be energized at the time determined by the position of the readout brush 42 in the related order.

Transferring circuits.—When it is desired to transfer an amount from the MC accumulator to any of the others, the connection 100 is made from the readout socket 96 to the contacts 1T2, 2T2 and 3T2 and further connection 101 is made to extend toward the adding magnet 32. Thus, with contacts 1T2 closed, for example, a circuit will extend from line 90, wire 98, emitter E2, wires 99, segments 41, brushes 40, readout strip 42, socket 96, connection 100, contacts 1T2, connections 101 and 97 to socket 92, and thence through magnet 32 to line 80. The magnet 32 of ACC#1 will thus be energized in accordance with the amount standing on accumulator MC.

Gathering circuits.—When it is desired to gather the sub-products from ACC#1 and ACC#2 into ACC#3, a plug connection 102 is made to contacts 1G2 and a connection 103 is made to contacts 2G2. Further connections 104 and 105 are made from these contacts to sockets 92 of ACC#3 in the proper denominational positions. When contacts 1G2 are closed, the gathering circuit which is similar to the above described transferring circuit will follow from the common strip 42 in the units order of ACC#1 through connection 102, contacts 1G2, connections 104, socket 92 of the hundreds order of ACC#3 and thence through magnet 32 in that order to line 80.

If contacts 2G2 are closed, a similar circuit is traceable from the readout strip 42 in the units order of ACC#2 through connection 103, contacts 2G2, connection 105 to the socket 93 in the tens order of ACC#3 and thence through the adding magnet 32 of that order.

Product printing circuits.—When the final product is to be printed, contacts P5 are closed and through plug connections 106 and 107 made thereto, circuits may be traced from the readout strip 42 in the units order of ACC#3, through connection 106, contacts P5, connection 107, printing magnet 58, to line 80.

The above describes briefly the manner in which the different circuits are completed and in Fig. 1b has been shown the plug connections 60 for a single order of each of the accumulators. It will be understood that similar connections are made in the other positions. It remains now to explain the manner in which the sequence of operations is determined so that the doubling, transferring and gathering circuits take place in proper order for the different problems.

Circuit selecting mechanism

Referring to Table I, it will be noted that for each of the accumulators #1, #2, and #3, the number of doubling and transferring cycles will depend upon the value of the multiplier digit associated with that accumulator. For example, if the multiplier digit associated with ACC#1 were "9", it would be necessary to cause such accumulator to double itself three times and to receive the amount in the MC accumulator by transferring once. The mechanism shown in Fig. 1a is designed to predetermine and bring about the proper type and number of doubling and transfer cycles required for each of the digits.

Referring now to Fig. 1a, for each of the accumulators there is provided an emitter 1E3, 2E3, or 3E3, provided with eight segments

traversed by the constantly rotating emitter brush. the common ring of each emitter is wired to a plug socket 108 through relay contacts H3 (which are controlled by relay H) from which socket plug connection 109 is made to the socket of the lower brush LB which traverses the multiplier field of the card. The emitter brush traverses the segments 9, 8, 7, etc., as the corresponding index point positions of the multiplier field pass the lower brushes and upon the sensing of a perforation in any of the digit positions, a circuit will be completed at such time which is traceable from line 90, contacts CR9, contacts LCL, lower brush LB, connection 109, socket 108, contacts H3, the emitter segment corresponding to the perforation sensed, wire 110, magnet K, wire 111, to line 80. Magnet K will close its contacts K1 to provide a holding circuit from line 80, wire 111, magnet K, contacts K1, wire 112, cam contacts TP1, wire 113, to line 90. Thus, for the example of Fig. 2, where the multiplier is 375, the "5" magnet K would be energized through the emitter 1E3; the "7" magnet K would be energized through its emitter 2E3; and the "3" magnet K would be energized through the emitter 3E3, and these magnets would remain energized throughout the subsequent calculating cycles, and until the commencement of the total printing cycle, at which time contacts TP1 open. Magnets K also cause closure of relay contacts K2 and K3 through which the doubling and transfer circuit controlling relay magnets D and T are energized. These contacts K2 and K3 of each order of the multiplier are connected by wires 114 to a group of vertical wires 115 through each of which wires current is passed in succession during successive cycles. A separate group of wires 115 is provided for each multiplier order.

Specifically, the first wire 115 to the left of each group of wires is connected to one side of line during the third cycle of operation. The next wire is rendered live during the fourth cycle; the next line during the fifth cycle; and so on, and only so many of the wires 115 are rendered live as are necessary for the solution of the problem.

The manner of connection between the wires 114 and 115 is in accordance with Table I. For example, in the "9" position, the doubling magnet 1D is connected to three successive lines 115 so that doubling will take place in three successive cycles. The transfer magnet 1T is connected to the fourth line and will be energized to effect a transfer after the three doubling cycles have taken place. In the "8" position it will be seen that there are no K3 contacts and only K2 contacts are provided which are connected to the first three wires 115 to bring about doubling in three successive cycles.

The lines 115 of each group are connected to a set of commutator segments 116 of a stepping relay whose contact arms 117 are secured to a spring-biased lever 118 which is advanced through pawl and ratchet 119 under control of a magnet 120. The ratchet is held in position by a retaining pawl 121 which is controlled by releasing magnet 122. The operation is such that during the first cycle in which the card passes the upper brush station and the cycle controlling magnets C are set up to energize relay magnet Y (Fig. 1), the related contacts Y5 (Fig. 1a) are closed so that near the end of this cycle, contacts CR2 will complete a circuit from line 80, contacts Y5, contacts CR2, stepping magnet 120, contacts P6, 1G6, 2G6 to line 90.

Stepping of the relay will advance the arms 117 from the "1" to the "2" position, which they occupy during the second cycle wherein the card passes the lower brushes and entries are made into the several accumulators, and during such cycle also the relay magnets K are set up in accordance with the value of the multiplier. Near the end of this second cycle, magnet 120 is again energized and the arms 117 are advanced to the "3" position where they bridge the segments 116 in that position and the common arcuate strips 123. Thus during the next succeeding or third cycle, a circuit is traceable from line 90, through contacts 2G6, 1G6, P6, then branching through the three strips 123, the wipers of arms 117, segments 116, the first wire 115 in each group. From these wires 115 the circuit will continue according to the setting of the K2 and K3 contacts to effect either doubling or transferring operations separately for each of the accumulators #1, #2, or #3.

For each cycle of operation the arms 117 are advanced to connect the next wires 115 to the line and this goes on until the cycle controlling magnets C have all been reenergized, at which time, as explained above, the magnet Y is short circuited and as a consequence its contacts Y5 (Fig. 1a) open, thus preventing further stepping of the arm 117. Also, as explained above, upon deenergization of magnet Y, the gathering magnet 1G (Fig. 1) is energized. This magnet also controls the contacts 1G2 (Fig. 1b) to complete the gathering circuits and thereafter the second gathering magnet 2G is energized to control the contacts 2G2 of Fig. 1b to effect a further gathering, and following this the magnet P is energized to close contacts P5 of Fig. 1b to permit printing circuits to be completed.

During these gathering and printing cycles, one of the contacts P6, 1G6 and 2G6 (Fig. 1a) is open to prevent any energization of the D or T magnets through lines 115. During the ultimate printing cycle, cam contacts TP2 (Fig. 1a) close to energize reset magnet 122 so that the arm 117 may return to its initial position.

It will be observed that where a multiplier digit is unity, that none of the K magnets related to that order are energized so that no doubling or transferring takes place for that accumulator. The same is true where the multiplier digit is zero and that in addition the initial entry for the related accumulator is suppressed.

Recapitulation

The operation of the main form of the invention will now be reviewed with particular reference to the problem of Fig. 2 to point out the sequence of operations. When the machine is first started, switch 11 is closed and motor M is placed in operation, so that the constantly running CR cams and emitters function. The brush of emitter E4 will make a number of revolutions during which the relay magnets C-6C will be energized in succession and holding circuits will maintain them energized. The start key is then depressed to bring about a preliminary card feeding cycle which advances the first record card to the position designated R in Fig. 5. During this cycle, the relay magnet H is energized, but this has no effect during this cycle.

First card feed cycle.—The start key is now operated a second time to energize the card feed clutch magnet 25, so that the card now passes the upper bush UB. As the card traverses the brushes the MP amount is sensed and circuits

through contacts **L1** are completed to energize the magnets **1B**—**6B** in accordance with the value of the **MP** digits. With particular reference to Fig. 2, this is the cycle designated **1** in such figure and where the multiplier factor is **375**, as in the example, the highest order magnet **6B** is energized. At the **0** time the contacts **L1** are open and contacts **L2** close so that relay magnets **1A**—**3A** may be energized if **0**'s are present.

- 10** The energization of magnet **6B** has caused magnet **Y** to become energized and a holding circuit provided therefor. During this same cycle, when the brush of emitter **E4** reaches its segment **g**, the relay magnet **C** is energized and held. The magnet **Y** opens its contact **Y2** to prevent energization in the gathering magnet **1G** when contacts **CR3** close later in the cycle, and a further pair of contacts **Y5** are closed to commence the operation of the stepping relay.

20 *Second card feed cycle.*—During this cycle, the card passes the lower brushes and circuits are completed to enter the **MC** amount into each of the accumulators through the now closed contacts **H2** and at the same time the **MP** amount is

- 25** entered into the **K** relays through the contacts **H3**. For the example of Fig. 2, therefore, accumulators **MC**, **1**, **2** and **3** each receive the amount **642** and through the emitters **1E3**, **2E3** and **3E3**, the **3**, **7** and **5** relay magnets **K** of the three sets **30** of relays respectively are energized and held to represent the setting of the **MP** amount **375**. During this cycle, when the brush of emitter **E4** is at the **f** segment, relay **1C** is picked up and the stepping relay advanced to the **3** position.

35 *Third cycle.*—During this cycle the relay magnets **1D**, **2D**, and **3D** are energized and close their respective contacts **1D2**, **2D2**, **3D2** through which circuits are completed from the readout devices of the accumulators Nos. **1**, **2** and **3** to their related adding magnets, whereby the amount in each of these accumulators is doubled as indicated along line **3** of Fig. 2. During this cycle relay magnet **2C** is energized.

Fourth cycle.—During this fourth cycle, the relay magnets **1T**, **2D** and **3D** are energized, causing a transfer from the **MC** accumulator to accumulator **No. 1** and further doubling of the amounts in accumulators **No. 2** and **No. 3**. During this cycle the relay magnet **C3** is energized.

Fifth cycle.—During this cycle the relay magnets **2T** and **3T** are energized, causing the amount in the **MC** accumulator to be concurrently transferred to the **No. 2** and **No. 3** accumulators. During this cycle relay magnet **C4** is energized.

Sixth cycle.—During this cycle the relay magnet **2T** alone is energized and a single transfer is effected from the **MC** accumulator to accumulator **No. 2**. Also, during the cycle relay magnet **C5** is energized.

60 *Seventh cycle.*—During the seventh cycle relay magnet **2T** is again energized and the transfer from accumulator **MC** to accumulator **No. 2** repeated. During this cycle, when the brush of emitter **E4** is at the **a** segment, a circuit is completed to energize relay magnet **6C**, which energization completes the series circuit through the contacts **C2** and **6C2**, causing deenergization of the relay magnet **Y** and consequent closure of its contacts **Y2** so that, when contacts **CR3** close

- 65** at the end of the cycle, relay magnet **1G** is energized and a holding circuit established for it through contacts **CR4**, which maintains the relay energized throughout the entering portion of the next cycle.

Eighth cycle.—With magnet **1G** energized, its

contacts **1G2** direct entries from accumulator **No. 1** to accumulator **No. 3** to effect the first gathering operation represented along line **8** of Fig. 2. During this cycle contacts **CR5** close and magnet **2G** will be energized and held through contacts **CR6**.

Ninth cycle.—During this cycle the amount in accumulator **No. 2** is transferred to accumulator **No. 3** so that the latter now contains the complete product. During this cycle the cam contacts **CR1** close to energize relay magnet **P** whose contacts **P4** energize the print and reset clutch magnets and contacts **P5** connect the readout device of accumulator **No. 3** to the type bar magnets **58** so that during this cycle the amount standing in accumulator **No. 3** is printed and all the accumulators are then zeroized. Toward the end of the total printing cycle, cam contacts **TP3** close to energize the card feed clutch magnet, and operations are now repeated upon the second card in the same manner beginning with the operations identified above as "first card feed cycle."

Modification

A modified form of the arrangement is shown is Fig. 11 whereby the total number of cycles required to effect multiplication is less than that for the main form. This is brought about by re-arranging the order in which doubling and transferring cycles for certain of the digits take place, and may be readily understood from an inspection of the following table:

TABLE II

MP digit	3rd cycle	4th cycle	5th cycle	6th cycle	
9	Double	Double	Double		Transfer.
8	do	do	do		
7	do	Transfer	do		
6	do	do	do		Do.
5	do	Double	do		
4	do	do	Transfer		
3	do	Transfer			
2	do				
1					
0	(Disable entering)				

Comparison of this table with Table I will show that the maximum number of cycles required for the doubling and transferring operations is four, whereas in the main form, five cycles are required. The difference in the two tables lies in the manner of obtaining the sub-product for the digits **6** and **7**. In the main form the sub-product of **6** is obtained by the doubling operations followed by two transfer operations, and **7** by two doubling operations followed by three transfer operations. In the modified form, the **6** is obtained by a single doubling operation followed by a transfer operation and then a second doubling operation, while the **7** is obtained by a doubling operation followed by a transfer and then a doubling and then a second transfer operation. In this manner, a cycle of operation is saved when these digits are a part of the multiplier and the number of relays in the cycle control mechanism may be reduced.

Fig. 12 shows the modified arrangement of the circuits extending from the emitter **E1** and it will be noted that the relays **6B** and **6C** are dispensed with. The emitter segments **5**, **6** and **8** control the relay **4B** while the segments **7** and **9** control the segment **5B**. In Fig. 11 the sets of lines **115** now have each only four separate wires extending to segments **116** which are arranged

concentrically about the common conductor 123.

It will be observed that a doubling operation occurs in the third cycle in all cases except where the multiplier digit is "1" or "0." This fact permits the elimination of a number of relay contacts K2 and K3 by providing a pair of contacts Ka which are normally closed as shown in Fig. 11 so that during the third cycle the doubling magnet 1D is energized through a circuit extending from the "3" wire 115 to the lowermost wire 114, contacts Ka, magnet 1D, to line 80. This circuit will cause the initial doubling operation to take place. It will be observed that the relay K corresponding to the multiplier digit 2 is omitted and another relay substituted therefor which is wired to the "0" and "1" segments of the emitter 1E3. The presence of a "0" or a "1" will energize this lowermost relay K to open the contacts Ka so that the doubling circuit is not completed for these digits.

While there has been shown and described and pointed out the fundamental novel features of the invention as applied to two modifications, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is as follows:

1. In a machine of the class described, an accumulator, entering means therefor, means for controlling said entering means to enter an initial amount into the accumulator, means settable by the accumulator to represent the amount standing therein, means including said settable means for controlling said entering means to enter into the accumulator the amount standing on the settable means to double the amount therein, means for rendering said last named means effective, mechanism selectively settable in accordance with the value of a digit, cyclically operating control means, and means operated by said control means and said selectively settable means jointly for causing the operation of said rendering means, once or a plurality of times in succession, to effect doubling of said initially entered amount or repeated doubling thereof in accordance with the setting of said mechanism.

2. In a machine of the class described, record sensing means, a pair of accumulators, entering means for each, means for controlling said entering means to enter an initial amount in each accumulator, means for each accumulator settable thereby to represent the amount standing therein, means including the settable means of one accumulator for controlling the entering means of the same accumulator to enter therein the amount standing on its settable means to double the amount therein, means for rendering said last named means effective, means including the settable means of the second accumulator for controlling the entering means of the first accumulator to enter therein the amount standing on the settable means of the second accumulator to thereby transfer the amount in the second accumulator to the first accumulator, means for rendering said last named means effective, mechanism selectively settable in accordance with the value of a record card perforation, cyclically operating control means, means operated by said control means and said selectively settable means jointly for causing the operation of the first

named rendering means, once or a plurality of times in succession to effect doubling of the amount in the first accumulator or repeated doubling thereof in accordance with the selective setting of said mechanism, and further means operated, after the operation of said last named means and by said control means and said selectively settable means jointly, for causing the operation of the second named rendering means once or a plurality of times in succession to effect transferring or repeated transferring of the amount in the second accumulator to the first accumulator in accordance with the selective setting of said mechanism.

3. In a machine of the class described, an entry receiving device, an accumulator, means for effecting the entry of a like amount in each, means for reading out the amount in the accumulator and reentering the same to effect doubling of the amount therein, means for transferring the amount in the entry receiving device to said accumulator, means settable in accordance with the value of a digit and arranged to determine, for each digit set up, a sequence of operations for said doubling means and said transferring means to increase the initial amount in said accumulator to an amount representing the initial amount times the value of the digit set in said settable means, cyclically operating control means, means controlled by said control means and part of said settable means for effecting the operation of said doubling means in accordance with the digit set up, and further means controlled by said control means and another part of said settable means for effecting the operation of said transferring means in accordance with the digit set up.

4. The invention set forth in claim 3 in which the means settable in accordance with the value of a digit is arranged to determine a sequence of operations comprising, for each digit greater than 1, one or more doubling operations to raise the initial amount to the product of the amount times the digit, or the highest multiple of the amount obtainable by doubling and which is less than the product, followed by one or more transferring operations to further increase said highest doubled multiples to the product of the amount times the digit.

5. The invention set forth in claim 3 in which the means settable in accordance with the value of a digit is arranged to determine the sequence of doubling and transferring operations so that for any digit set up there will be a maximum of five successive operations with doubling operations preceding transferring operations.

6. The invention set forth in claim 3 in which the means settable in accordance with the value of a digit is arranged to determine the sequence of doubling and transferring operations with interchanged order of doubling and transferring operations so that for any digit set up there will be a maximum of four successive operations.

7. In a multiplying machine, a pair of accumulators, entering means for each accumulator, means for causing said entering means to enter a multiplicand factor in each accumulator, readout mechanism for each accumulator, separate connecting means for connecting the readout mechanism of one of said accumulators to the entering means of the other accumulator, further connecting means for connecting the readout mechanism of said other accumulator to its related entering means, a relay for rendering said first named connecting means effective, a second

relay for rendering the second named connecting means effective, a device settable to represent any multiplier digit greater than 1, a cyclically operating mechanism, circuit connections completed through said relays under joint control of said device and said mechanism in accordance with the setting of said device, to render said connections effective in a predetermined sequence, an emitter coordinated with said cyclically operating mechanism for effecting transferring of the amounts standing in said readout mechanisms, through the connections rendered effective by the relays, to the said other accumulator whereby upon operation of the entering means the multiplicand factor entered therein will be increased to an amount representing the product of the factor by the multiplier digit.

8. In a multiplying machine, an entry receiving device, a plurality of accumulators, entering means for said device and for each of said accumulators, a readout device for said entry receiving device and for each accumulator, transferring connections between the readout device of said entry receiving device and the entering means of each accumulator, doubling connections for each accumulator between the readout device of each accumulator and the related entering means thereof, means for causing said entering means to initially enter a multiplicand amount into said entry receiving device and the same amount into each accumulator, means for causing the amounts standing in the several readout devices to be transmitted to the several entering means through said connections, a multiplier set up device for each accumulator, each settable to represent a multiplier digit greater than 1, means for each accumulator for completing its related transferring connections, means for each accumulator for completing its related doubling connections, a cyclically operable control means for each multiplier set up device, means jointly controlled by each control means and its related multiplier set up device for causing completion of the related doubling and transferring connections in accordance with the digit set up and in a predetermined sequence to raise the amount initially entered in the related accumulator to the product of said amount by the multiplier digit, each of said control means operating concurrently whereby products will be formed concurrently in all the accumulators.

9. The invention set forth in claim 8 in which transmitting means including connections are provided between the readout device of one accumulator and the entering means of another, together with means for completing said connections when all the products have been obtained, said transmitting means thereupon causing the

product in said one accumulator to be transmitted to said other accumulator.

10. The invention set forth in claim 8 in which a further accumulator and entering means therefor are provided and in which transmitting means including connections are provided between the readout devices of each of the first named accumulators and the entering means of said further accumulator, together with means for completing the transmitting connections from each readout device in turn when all the products have been obtained, said transmitting means causing the product in each accumulator to be transmitted in turn to said further accumulator. 10

11. In a machine of the class described, means 15 for sensing a record card for perforations representing a multiplier amount, means for sensing said card for perforations representing a multiplicand amount, a plurality of accumulators, one for each possible digital position of the multiplier, 20 entering means for each accumulator, connections between said second named sensing means and the entering means of each accumulator for enabling the multiplicand to be entered from said card into each accumulator, means controlled by said first named sensing means for ascertaining the digital positions in which significant multiplier digits occur, and means controlled thereby for rendering said connections ineffective to enter the multiplicand in accumulators whose 30 related multiplier digital positions do not contain a significant digit.

12. In a machine of the class described, an accumulator, entering means therefor, a settable device, means for entering an amount therein, 35 means for causing said entering means to enter a like amount in said accumulator and in said device, means for reading out the amount in said accumulator and reentering the same therein to effect doubling of the said amount, controlling 40 means therefor to render said doubling means effective, means for transferring the amount in said settable device to said accumulator, controlling means therefor to render said transferring means effective, means settable to represent certain digits, cyclically operated control means and devices controlled by said settable means and said control means jointly and in accordance with the digit represented for selectively causing the control means for the doubling means to operate once 45 or a plurality of times and for thereafter selectively causing the control means for the transferring means to operate once or a plurality of times whereby the amount initially entered in the accumulator will be increased to the product of said amount by the digit represented on said settable means. 50
